UNITED STATES PATENT OFFICE.

RUDOLPH M. HUNTER, OF PHILADELPHIA, PENNSYLVANIA.

PROCESS FOR MANUFACTURE OF ENAMELED LEATHERS.

1,182,013.

Specification of Letters Patent.

Patented May 9, 1916.

Application filed February 9, 1910. Serial No. 542,880.

To all whom it may concern:

Be it known that I, RUDOLPH M. HUNTER, a citizen of the United States, and resident of the city and county of Philadelphia and 5 State of Pennsylvania, have invented an Improvement in Processes for Manufacture of Enameled Leathers, of which the following is a specification.

My invention has reference to processes 10 for manufacture of enameled leathers and consists of certain improvements which are fully set out in the following specification and shown in the accompanying drawings which form a part thereof.

15 My invention has reference broadly to the preparation of leathers with a polished or enameled coating such as provided on patent-leather, enamel-kid, etc., in which the surface of the leather is first dyed or 20 colored and subsequently enameled by a coating of varnish having proper qualities.

25 I will describe my invention more particularly with respect to the manufacture of enameled-kid, and from which description, the general characteristics of my improved methods for making enameled-leathers, as well as the apparatus for the purpose of carrying it commercially into effect, will be fully understood. Any form 30 of leather with an enameled surface may be produced by my improved process and apparatus and any modification in appearance will be due to variations in the character of the leather, coloring and varnishing 35 thereof, rather than to the difference of the method or means employed in its production.

40 In the production of enameled-leather, it has heretofore been the practice to first stretch the skin on a frame and then coat the skin with a "daub", which may consist of a collodion compound made of gun-cotton and amyl acetate, which acts as a filler and water-proof coating, the said "daub" being 45 colored by nigrosin or otherwise to give the black or colored ground for the enamel. The leather, so treated, is allowed to dry, preferably in the sun for six hours, or lacking sunshine, in a closed oven heated to 50 about 120 degrees Fahr. for a like period, and is then rubbed down with pumice stone to make its coated surface smooth. The leather is then varnished with a solution of boiled linseed oil thinned down with turpen- 55 tine and colored with Prussian blue ground in oil, or other coloring ingredients where

the patent-leather is to be colored. The leather, in its varnished condition, is then put into an oven and baked at a temperature of about 140° or upward Fahr. for thirty to 60 forty-eight hours, the oven being a closed affair having no outlets or inlets and heated by steam pipes. The baking being completed, the leather is then removed from the oven, and is next exposed to the sun in the open 65 air until all tackiness is removed. This latter operation usually requires from thirty-six to seventy-two hours additional. The operation of pumice-stoning, varnishing, baking and sunning may be repeated if so 70 desired as often as required to secure the degrees of finish to the patent-leather which may be demanded. Experience has shown that serious objections are found in this process, which may be briefly referred to as 75 follows:—The time required for the drying of the "daub" coating is undesirably long, being not less than six and frequently approximating ten hours, and is objectionable in that it depends upon atmospheric conditions, or those involving a high temperature 80 in a closed draftless oven with the result that the leather is materially injured in texture and frequently burned. The time required to bake the varnished leather is 85 excessively long, and yet from the nature of the process, it has not heretofore been possible to shorten it. The baking of the leather in the closed oven maintains the turpentine or other solvent in contact with the 90 leather for an objectionably long period, and moreover, because of the volatile nature of the turpentine, it rises to the higher part of the furnace, with the result that the skins which are near the bottom or next the heating coils are baked to a greater and more 95 dry condition than the skins adjacent to the upper part of the drier chamber, thereby requiring unequal times in the final or sunning process in removing the tackiness. 100 This irregularity in the production of the baked skins necessitates more careful handling and watching in the drying operation.

105 Experience has shown that at least two or four skins out of every set of sixty skins, constituting the charge for each oven, are injured by over-baking or burning with each treatment, said skins being those stretched upon the first and second frames and nearest to the heating coils or pipes from which 110 the oven derives its heat. These skins are either rendered useless or must be sold in the

finished state as seconds at considerable loss to the manufacturer. The sunning operation is objectionable; first, in that it necessitates dry clear weather, which frequently does not occur for considerable periods at certain times of the year. So troublesome has this been during some years that it has been impossible for manufacturers to fill their orders, and not infrequently this trouble has caused ruination of the manufacturer. The second objection to the sunning process lies in the fact that the frames containing the stretched and baked skins are required to be taken from the ovens and placed in the open air so as to be acted upon by the sun, necessitating great labor, loss of time, and causing much loss by injury to the skins and frames by careless handling; and where the varnishing is performed a number of times on the same skins, the loss of time from this cause is very important, because the transferring of the frames is largely done by skilled workmen who, at other times, are preparing the skins. And further, objection lies in the fact that at certain times of the year storms are liable to occur unexpectedly, and if, at such times, the skins are not quickly removed into shelter, they will be injured by the rain; such state of affairs being a source of constant worry and anxiety to the manufacturer and frequently of very great loss. A still further objection to this part of the process lies in the fact that the skins, being exposed in the open air while they are still tacky, very frequently become injured owing to the blowing of dust on windy days, which dust adheres to the surface and dulls the leather. Furthermore, on very hot dry days the varnished surface of the leather is liable to become discolored by what are known as sun spots, a condition which destroys its salability.

The foregoing are the main objectionable features incident to the present method of manufacturing enameled leather, and which it is the object of my invention to overcome. The objects of my invention, not only are to overcome each and all of the above existing objections, but also to greatly increase the output of a given number of ovens, to reduce the number of skilled workmen necessary for a given output in skins, to produce absolute uniformity in the character of all the skins treated, to greatly reduce the time required to complete the enameling of the skins, to eliminate all handling of the skins after being varnished and up to the completion of the process, to prevent any burning or over-baking, to provide capacity for producing the enameled leather irrespective of the condition of the atmosphere and to insure the manufacturer being able to regularly produce a given number of enameled skins within any given period whereby he

may carry on his business with every degree of confidence.

The object of my invention is further, to greatly cheapen the cost of enameling the skins, and as the result of the advantages above enumerated and by reason of the facts hereinafter set out, I have found, by actual experience, that the cost heretofore required to enamel the skins, (exclusive of the cost of the skins) may be reduced fifty per cent. 75 by use of my improved process and apparatus, said saving equaling upward of \$55,000,000 upon the present enameled leather output in the United States alone; and moreover, the said saving may be had 80 while producing a better finished and more marketable product.

My invention consists in a method of treating the leather and in the means employed therefor, whereby said method may 85 be carried into commercial effect, which method and means are more fully described hereinafter and defined in the claims.

In general, my improved method may be stated to consist in first drying the 90 stretched leather, after it has been coated with the filling and coloring matter or "daub", within an oven or closed chamber through which a current of heated air is caused to slowly pass, the same being preferably allowed to go to waste after acting upon the leather. This operation requires approximately three hours and under a temperature of 120° Fahr. The dried "daub" coated leather is then removed, and after 100 being pumice-stoned, is varnished and reinserted into the oven, and subjected to a forced continuous circulation of preferably the same heated air at temperatures preferably ranging from 120° to 140° Fahr., and 105 preferably removing the turpentine from the air during its circulation, the said air being caused to pass over all of the different skins and kept in constant motion while maintaining the high temperature. After 110 treatments under special conditions of approximately twenty-five hours, the varnished leather is brought to a baked condition and comparatively free from the volatile turpentine, and it is then treated to 115 circulating air at a temperature of approximately 145 degrees Fahr. or higher for nine hours more, resulting in a condition of dryness in which there will be some tackiness, which is removed by then reducing the temperature of the oven to atmospheric temperature, and preferably not over 95 degrees Fahr., and performing this drying by air taken from outside of the building and, after acting upon the skins, allowing it to escape, so as to cause large quantities of dry cool air to pass over the surface of the varnished leather to remove the last trace of the turpentine and chill the surface of the 125 enamel. This latter treatment would ordinary 130

narily be carried on for three hours, after which time the frames may be withdrawn from the oven and the skins will be found to be free from all tackiness and with a 5 most perfect luster and uniform in character. The circulation of the air insures all the skins being treated alike, and prevents excessive heating and burning of the skins next to the heating coils. No handling of 10 the skins through the entire baking and drying processes is required, as all actual manipulations are carried on with respect to the circulation of the air and the temperatures under which it is maintained. 15 The preliminary drying process for the drying of the "daub" coating may be omitted if desired, and the said drying be carried on in warm rooms or in the open atmosphere, if so preferred; though it is far 20 more desirable to dry the same in the ovens under the conditions above specified; namely the circulation of heated air over the coated leather without re-circulating the same air.

It will be understood that in giving temperatures and time of treatments, I have given those which I have found most advantageous, and said data are given by way of illustration and not as a limitation upon my invention.

30 My invention will be better understood by reference to the drawings, in which:—

Figure 1 is a transverse sectional elevation of an oven embodying my invention and in which to carry my improved method 35 into practice, the same being taken on line $x-x$ of Fig. 2; Fig. 2 is a longitudinal sectional elevation of the same taken on line $y-y$ of Fig. 1; Fig. 3 is a plan view of a plurality of my improved ovens with associated apparatus for commercially carrying 40 my process into practice upon a large scale; Fig. 4 is an elevation of the same; Fig. 5 is a cross section on line $s-s$ of Fig. 4 showing the inlet valves for the ovens; and 45 Fig. 6 is a similar cross section on line $t-t$ showing the outlet valves for the ovens.

I will first describe the construction and 50 operation of the single oven shown in Figs. 1 and 2 and then consider the use of the apparatus and method when employing the plurality of ovens as shown in Figs. 3 to 6 inclusive.

The oven consists essentially of a chamber 2 having heat insulating walls 3 about it of 55 any suitable construction and commonly formed by double walls of wood with air spaces between. The oven chamber is closed on all sides but the front, which is open for the full width and height and provided 60 with removable hinged doors 19, each of small vertical height, arranged one above the other, so that the front may be gradually closed up and made comparatively tight as the oven receives the frames with the skins stretched upon them. These doors may be

made in any suitable manner, and I do not wish myself to be restricted in any respect as to their construction. The lower part of the chamber 2 may be provided with heating coils 12 through which steam may be 70 passed and controlled by means of a hand valve 20 arranged immediately outside of the oven. The steam coils 12 are arranged within the compartment 8 at the bottom of the oven and into which air is supplied at 75 one side by a conduit 10, which may be provided with a suitable valve 11 to control or shut off the supply of air. The other side of the compartment 8 is open, as at 9, said opening extending along one side of the 80 oven. Each of the interior side walls of the oven are provided with upright studs 4, and upon these are secured horizontal angle irons 6, arranged parallel and at a distance above each other to form guides upon which 85 the leather supporting frames 7 rest. By means of these guides, the frames 7 are enabled to be shoved into position and be supported at a short distance above each other. The skins to be treated are stretched upon 90 or secured to the open frames 7 in any of the well known manners employed in the manufacture of enameled or patent-leather. The studs 4 provide, as it were, a series of vertical passages 5 between the guides 6 and 95 the side walls of the oven, through which the heated air may pass to reach each one of the frames. Moreover, the said vertical passages 5 have communication with the interior chamber 2 between the angle iron guides 100 6, so that a current of air may pass upward at one side of the oven, thence horizontally across between the various frames 7 and into the vertical passages 5 at the other side of the oven and thence upward, escaping at the 105 top into a header 13, from which flues 14 and 15 open, the former leading to the atmosphere, or to a chimney or other draft producing device, such as a fan, and the latter leading to means for circulating the air over again through the oven as described herein- 110 after. A valve 16 is so pivoted as to control the entrance of air to either of the flues or conduits 14 and 15. The valve shown is pivoted and adapted to be oscillated by a hand rod 18 and is counter-weighted at 17, so that when it is thrown into the position indicated in full lines, or into the position indicated in dotted lines, the said counter- 115 weight 17 will hold the valve in such as- sumed position. While the upper end of the passage or flues 5 at one side of the oven discharges the heated air into the header 13 at the top of the oven, the corresponding flues or passages 5 at the other side of the oven receives the hot air from the open end 9 of the steam heated compartment 8 at the bottom of the oven.

It will readily be understood that, by 120 means of the construction above described, 130

it is possible to cause a uniform circulation of the air and gases over each of the frames 7 and their skins, so that the said skins are treated both above and below to currents of air, it being understood that the frames are of the usual open construction which expose both sides of the stretched skins. It will, further, be observed that all of the skins are subjected to air currents to substantially the same extent, because the resistance to the flow of the air through the oven is substantially the same with respect to every frame within it. In an oven of this character the skins may be stretched completely over the entire openings in the frames 7, such as would sometimes occur where side leather was employed, as distinguished from kid, and yet both sides of the skin would be equally heated and dried. Furthermore, the air is carried away from the oven immediately after it has become impregnated with the turpentine or other volatile gases expelled by the heat, so that drying is performed in a speedy manner and with great uniformity in respect to each and every skin in the entire oven. From this it is evident that, unlike the ovens formerly employed in the manufacture of patent-leather, there is no possibility of the lower treated skins becoming dried up or burned by being too near the heating coils, or of the upper skins becoming over-saturated or half dried because of the accumulation of turpentine from the varnish or volatile gases from the "daub" in the upper part of the oven. Furthermore, the action is such, that there is no tendency of dripping of the turpentine and varnish from one skin to the other, because the volatile substances which may tend to form drippings are rapidly conveyed away as quickly as formed, and the result, in practice is, that all of the skins are uniformly dried and said drying is accomplished in a speedy and efficient manner. In view of the special manner of circulating the air, and broadly, because of the fact that the air is circulated and not allowed to remain in a stagnant form in the oven, as heretofore, the drying operation of patent-leather is accomplished in a fraction of the time which has heretofore been required; and moreover, the leather when taken from the oven, is devoid of any tackiness, a condition which has never before been possible under the methods formerly employed wherein the treatment in the oven is carried on without the elimination of the volatile turpentine and other gases produced by action of the oven upon the prepared leather.

While I prefer to provide the compartment 8 at the bottom of the oven, to insure the heated air passing over the coils 12 and into the vertical passages 5 before being allowed to flow upward, it is evident that, broadly considered, this compartment might

be dispensed with where the frames 7 have their openings only partly covered with leather, such as when kid-skins are being enameled, because in that case, there are considerable openings through which the heated air may pass upward through the oven chamber and escape by the flues 14 and 15, as required. I have found that the vertical passages 5 and the lateral openings between the guides 6 may be dispensed with and reasonably fair results secured whenever the skins to be enameled cover only a portion of the openings in the frame 7 as aforesaid, but in the cases where large skins are to be enameled, and when the free vertical passage for the air through the oven by way of the frames is prevented, then, in those cases it becomes practically essential to provide the side passages 5 with the lateral openings therefrom leading into the chamber 2 and between the successive frames, as shown. In fact, this form of oven is considered far superior to the construction in which the oven is simply supplied with the inlet and outlets, respectively, at the bottom and top and relying on the passage of the air through the frames, and I prefer in all cases to employ the type of oven here shown and fully described.

In drying out the skins which have been treated to the "daub" coating after they are stretched upon the frames 7, the said frames are placed in the oven and the valve 16 is adjusted to the position shown in Fig. 1. Air is then supplied by the duct 10 through the valve 11 and caused to pass over the heating coils 12 to attain the desired temperature, thence through the oven, as indicated by the arrows, carrying off the volatile vapors or gases from the "daub" coating on the various skins, said air current delivering the said vapors or gases into the flue 14, which may lead directly into the chimney of the factory, or may deliver into any suitable apparatus for condensing and collecting the vapors. In this part of the process, the current of air and the extent of its heating is controlled with a view of insuring the most speedy drying consistent with proper maintenance of the conditions of the skins and the "daub," and this regulation may be performed by the control of the valve 11 and the steam valve 20. The air delivered through the duct 10 may be supplied directly from the atmosphere by natural draft or by means of a blower and may be heated or not as desired, before being delivered to compartment 8. In practice, I have found that, by the employment of my improved oven maintained at a working temperature of about 120 degrees Fahr. and a slowly circulating current of air through it, the "daub" coating may be dried in a most perfect manner within three hours, instead of requiring the six hours or more

heretofore necessary in sun drying under the old method. After the "daub" coating has been thoroughly dried it is pumice-stoned to impart to it the desired smoothness, and the stretched leather is then varnished and reinserted into the oven. When the oven has been filled with frames 7 containing varnished skins, the valve 16 is adjusted to the dotted position, and the air, which enters 5 by the duct 10, is heated to the desired temperature in passing over the coils 12 and then circulated through the oven, as indicated by the arrows in Fig. 1, so that all of the skins are equally treated. The volatile 10 vapors of turpentine which are given off from the varnish on the skins are conveyed by the air into the header 13, and thence by the duct 15 to a suitable condenser, and thence to a heater, and back to the duct 10, 15 as will be later more fully described. The volatile turpentine vapors are thus removed from the oven chamber 2 and away from the skins as soon as formed, and by means of the condenser are taken out of the circulation. 20 The air may thus be circulated over and over again through the oven chamber until the proper degree of drying of the varnish has been secured. The temperature of the air must not be raised too high at 25 30 the preliminary operation of drying for the reason that there will be a tendency to form bubbles from too rapid escape of the turpentine or solvents in the varnish, and this would produce defective surfaces in the finished product. The best results are secured 35 by a temperature of about 120 degrees Fahr. during the preliminary or "setting" operation of drying of the varnish which consumes about one hour, and an increase of 40 that temperature to 135 degrees Fahr. during the continued recirculation of the air for a period of twenty four hours, in which the baking of the varnish takes place. When 45 the volatile gases have been largely eliminated and the baking completed, it is then possible to raise the temperature of the air circulating over the skins in the drying operation without producing surface defects and the temperature may therefore be raised 50 considerably higher (so long as the leather is not burned) and circulation maintained for a period of nine hours, and in this manner the drying is almost completed, the final removal of all tackiness from the surface 55 of the skin being accomplished by shutting off the heat and circulating cold air through the oven and allowing it to escape to the chimney by flue 14. In the first or setting operation, in the drying of the varnish, the 60 air and volatile vapors escaping from the oven may be allowed to go to the chimney by way of flue 14 instead of passing to a condenser; and in place of being heated to 120 degrees Fahr., the air, employed in this setting operation, may have a less temperature. 65

In the last or final operation to remove the tackiness, the cooler the air which is circulated through the oven, the more satisfactory the result; but in cases where the absolute humidity of the atmosphere is exceptionally high, it is desirable to lower its relative humidity by heating it to some extent before circulating through the oven. Under other conditions, this heating of the air will not be necessary or advisable. 70

Where it is not desired to save the volatile solvent in the varnish, the air which is laden with said solvents may be allowed to escape through the flue 14 by adjusting the valve 16 into the position indicated in solid lines in Fig. 1, performing thereby the same operation of drying which was carried out in the case of drying the "daub" coating. In this way there will be some increase in the speed of drying because of the complete elimination 75 of all volatile matters from the drying air at a time when the varnish is in a very fluid or plastic condition. After the main volatile vapors have been eliminated by the drying operation, the valve 16 may be shifted 80 to the dotted position and the air then recirculated with or without the employment of the condenser and the external heater, if so desired. This latter operation is desirable 85 because the recirculation of the air enables the drying operation to be carried on with less loss of heat; and this is material in the 90 operation of my process by a large plant when carried over a considerable period of time. 95

In actual operation, there is a great saving 100 in time required by my method of drying the varnish over that required by the process now in general use. For example, the operation of "setting" and baking by my 105 process requires 25 hours, whereas in the method now in use, the time necessary is 36 hours; and the operation of drying requires, by my method, 12 hours, whereas in the 110 method now in use 36 to 72 hours are actually required, when it is possible to dry at all. This latter is most important to be taken into consideration, because the old method being a "sun drying" process, is dependent solely upon the existence of a dry 115 atmosphere and sunshine, two conditions which are frequently lacking, and because of which, no certainty has heretofore existed in the "output" in finished leather from a factory. This trouble is entirely obviated by the use of my improved process. 120

The foregoing description has been directed to a single oven which, of course, may be operated as an individual element in an enamel or patent-leather plant, but in commercial practice there will be, ordinarily employed, a number of such ovens, located side by side, and these may be arranged in any suitable manner to receive the supply 125 of air from a common source and to deliver 130

the air laden with the vapors to a common escape flue, or otherwise, as hereinafter explained.

Referring more particularly to Figs. 3, 4, 5 and 6, a plurality of ovens is indicated at 2^a, and of these there may be any number. The upper headers 13 of these ovens communicate with two longitudinal conduits 21 and 22 by means of suitable valves indicated at 16^a, and in this case for convenience, the valves may be in the form of slides in place of being pivoted, as shown in Fig. 1. The flue 21 communicates with an upright flue 14 corresponding to the flue 14 in Fig. 1, and this may lead to the chimney or other outlet to the atmosphere. A draft device, in the form of a blower 32, may be employed to create a suction from the conduit 21 to more quickly withdraw the vapor laden air from the various ovens. Natural draft might be sufficient in some cases without the use of any blower, or other draft creating device. The other conduit 22, in communication with the headers 13, leads to a condenser 23 having a cooling coil or other condensing surface 24 through which cold water, or other cooling medium, may be made to flow. The bottom of the condenser may be provided with an overflow trap 25 of any suitable construction from which the condensed vapors of turpentine may escape and be collected for use again in the varnish. The air which passes through the condenser 23 is conveyed by a pipe 26 to a heater 33 of any suitable construction, and from the heater the heated air may pass by a pipe 27 to the suction side of a blower 28 by which the circulation of the air may be produced or assisted. The discharge side of the blower 28 communicates with a conduit 10 which corresponds to the conduit 10 in Fig. 1. From this conduit the air may pass through the valves 11^a into the conduits 10^a leading into the chambers 8 in the ovens. The valve 11^a performs the function of the valve 11 in Fig. 1. In this manner the air may be recirculated through the various ovens over and over again and the vapors of turpentine may be largely removed from the circulation and collected by being brought into contact with the condensing surface 24 in the condenser. In this way, the drying atmosphere to which the skins are subjected is prevented from becoming saturated or over impregnated with the volatile turpentine vapors, whose presence would retard and prevent proper drying of the skins. The speed of circulation may be governed to a nicety by the control of the valves 11^a, and it is also evident that as each of the ovens is provided with independent valves, the speed of circulation in any oven may be varied with respect to the

speed of circulation in any other oven. This 65 enables the control of the circulation in the various ovens to suit the particular condition of the materials being treated in the oven at any particular time. Moreover, the apparatus may be operated continuously 70 and any oven may be put into or out of operation, or varied in temperature, or speed of circulation without interference with, or affecting the operation of any other of the ovens. This is important in a plant which 75 employs a large number of these ovens in the carrying on of its business. 29 is a second conduit, parallel to the conduit 10^a and may be put into communication with the conduits 10^a of the several ovens by valves, 80 which may, for convenience, be integral with the valve 11^a. This conduit 29 may lead to the atmosphere so that fresh air may be supplied to the several ovens, or any of them, and after acting upon the contents of the ovens, may be permitted to escape by the flues 21 and 14 into the chimney, this operation being substantially that which is preferred to be carried on in respect to the drying of the "daub" coating 85 of the leather. A branch pipe 30 may communicate with the conduit 29 for supplying fresh air to the suction side of the blower 28, and this conduit 30 may be controlled 90 by a valve 31, and by which a given amount of air may be introduced into circulation at any time to facilitate the drying operation. Moreover, this valve 31 may be opened when it is desired to quickly purify the chambers of any gases or vapors contained 95 within them, and which operation would be performed by simultaneously opening the valves 16^a to the conduit 21. In this case the fresh air would be drawn in through the conduit 10 into the oven or ovens, and 100 thence out through the conduit 21 into the flue 14 to the chimney. This operation may be employed as the final operation in the drying of the varnished leather, though the draft of the conduit 21 would be sufficient. 110 This same action would also enable all of the vapors which might be with the air in the circulating system to be driven out of the ovens and pipes generally, into the 115 chimney.

It will be observed that the conduit 22 and the conduit 10 respectively lead from and to the ovens from different directions to insure uniform resistance in the circulation through the several ovens, precisely for 120 the same reasons as the supply and discharge ends of the flues 5 in each oven are respectively at the bottom and top. This feature of uniform resistance of circulation through the plurality of ovens becomes important when twenty-five to one hundred ovens are employed in one plant, because by such arrangement the operation of any oven 125

or group of ovens cannot, in effect, short circuit the currents of drying medium required to flow through others of the ovens.

In cases where the humidity of the atmosphere is high or approximating saturation, as on rainy days, it will be desirable to raise its relative humidity as before stated and this may be done by opening the valve 34 in conduit 35 leading to the heater

10 33 and closing valve 31 in conduit 30, in which case, by the adjustment of valves 11^a and 16^a, the air, after being heated, is delivered into conduit 10 and thence through the ovens into the conduit 21 and by conduit

15 14 into the chimney.

I do not restrict myself to any particular details of construction of the ovens or of the connecting flues, or means for governing or controlling or inducing the circulation of the air through the ovens and over the stretched leather therein, as these may be varied or modified in many ways without changing or altering the operation or the results to be accomplished by the carrying out of my improved process.

In the operation of my improved arrangement of the plurality of ovens, the following process may be followed: The leather is stretched by tacking or fastening upon the frames in any suitable manner, and then coated with the "daub," which is prepared in the ordinary and well known manner to those familiar with the art of making patent or enameled leather. The frames containing the leather so prepared are then introduced into the ovens (as indicated in Figs. 1 and 2), and the temperature of the oven is raised to 120 degrees Fahr., being that required for drying out the "daub" coating. The drying operation is facilitated by arranging the valves 11^a and 16^a, for supplying the heated air under natural or forced draft through the ovens, the constant supply of fresh air passing over the heating coils 12 passing upward through the flues 5 at one side of the ovens, thence horizontally over and under the various stretched skins and their frames, thence into the flues at the opposite side of the ovens, and thence upward into headers 13 and from it into conduit 21 leading to the flue 14 connecting with the chimney. The speed of circulation of the air in this manner should be restricted to exactly that which is necessary, with the heating by the coils 12, to maintain the desired temperature in the oven, which ordinarily should be of approximately 120 degrees Fahr. The maintenance of this temperature may be controlled by the valves 11^a and from the indications of a suitable thermometer extending into the interior of the oven for indicating its temperature. If the temperature falls too low, the valves 11^a should be closed to a greater ex-

tent to restrict the inflow of fresh air, and on the other hand, should the temperature rise too high, the said valves may be opened to a greater extent; or the steam control valves 21 may be throttled to a greater or less extent to maintain the required temperature. It is somewhat important in this operation not to make too strong a draft of air through the oven, as too rapid a volatilization of the coating on the leather will have tendency to produce more or less unevenness due to bubbles formed on the surface. This, however, is not so apt to occur in the case of "daub" coats as with the varnish coats later to be applied to the leather. The circulation thus carried on conveys away from the ovens the volatile ether or other vapors which may be produced, as quickly as they are eliminated from the "daub" coating of the leather, so that the atmosphere in which the leather is contained is always maintained in a condition which readily absorbs the volatile constituents of the said "daub" coating, thereby enabling a speedy drying of the material in a uniform and effective manner. After the operation of drying of the "daub" coating has been performed, the frames 7 with their leather stretched thereon are withdrawn from the ovens and the "daub" coated surfaces are pumice-stoned, and thereby brought to the required smooth surface which is necessary in the manufacture of leather of this character. If desired, more than one "daub" coating may be applied and dried, and the same may be re-pumice-stoned, but ordinarily this is not necessary. The leather, when thus prepared with the finished "daub" coating, is next treated to a coating of varnish, which may be of the usual composition hereinbefore referred to. This varnish contains very volatile substances, of which turpentine is the essential one to be considered. The varnish may be of the character heretofore in common use in the manufacture of patent or enameled leather. The skins, carefully coated with the varnish, are then immediately inserted into the ovens, the doors 19 thereof placed in position, and the operation of drying the varnished surface is performed as follows: The valves 16^a are shifted so as to close the outlets from the ovens into the conduit 21 and to open the outlet into the conduit 22; likewise, the valves 11^a are shifted so as to close the communication between the ovens and the conduit 29 and open the communication between the ovens and the conduit 10. The blower 28 is then put into operation and the air, preferably about a temperature of 120 degrees Fahr., is slowly circulated through the ovens, through the condenser 23 and through the heater 33. The turpentine vapors which are liberated from the varnish

are conveyed from the ovens through the conduit 22 into the condenser 23, and are brought into contact with the cold surfaces of the condenser coils 24 and upon which the condensed vapors are deposited, and from which they run down to the bottom of the tank forming the body of the condenser and pass off through the trap 25 into suitable receptacles arranged to receive the liquid turpentine. This turpentine may be used over again in the making of more varnish. The chilling of the air by the condenser 23, incident to the condensing of the turpentine vapors, lowers the temperature of the air somewhat, and it is therefore desirable to again raise the air to the normal temperature by passing it through the heater 33 before being again circulated through the ovens 2^a. The temperature in each of the ovens is independently regulated by its own heating coils 12, but by heating the air externally to the ovens, less duty is required of the individual heaters 12, and hence, it is more easy to regulate the temperature within the oven to the desired extent to insure the proper drying operation whereby it will be as speedy as possible, without danger of producing bubbles on the surface from too rapid evaporation. After the setting of the varnish has been completed, the temperature of the ovens and air may be raised to 135 degrees Fahr. or higher and the circulation continued as before for a period of twenty four hours, more or less, to bake the varnished skins to still further densify the varnished coating. This baking causes the volatile vapors to be driven off and the varnish to be fully set, and after this has been done there is no further danger of bubbles forming, or cracking of the varnish by heat, and hence the skins are then in condition for the next operation, namely, drying.

The drying is accomplished as follows:-

The condenser may be shut off or put out of circuit by pipe 36 having valve 37, and the temperature of the ovens and air raised to 140 degrees Fahr. or upward and the circulation maintained for a period of about nine hours. While this drying operation is taking place, the varnish having become well set and largely free from volatile constituents, the temperature may be considerably raised according to the conditions of the air, I having used in practice temperatures as high as 155 degrees Fahr. with good effect. During this drying operation the air may be partly changed by partly opening the valve 34 and the valves 16^a, so that a portion of the circulating air may be allowed to escape to the chimney and a corresponding portion of fresh air admitted into the circulation. This will facilitate the drying, but care should be exercised to prevent the temperature becoming lowered, or a retardation of the process

will result. After about nine hours, under the drying operation, the varnish will have become dried, but still retains tackiness, and the valves 16^a and 31 may be then so adjusted as to provide means for full escape into the conduit 21 and thence to the chimney by flue 14, of the air from the ovens, while a corresponding amount of fresh cool air is permitted to pass through the pipe 30 and valve 31 into the circulation. Instead of the fresh air passing through the blower before passing into the ovens, it may be permitted to pass directly through the conduit 29, through valves 11^a and conduits 10^a into the ovens. In this final drying to remove tackiness, the air supplied to the ovens is best when in a cool and dry condition; but if it has too much humidity, it must be heated first by heater 33 before admittance to the ovens, as before set out. This final operation is ordinarily conducted with the heating coils 12 shut off, but these coils may be employed separately or in combination with the heater 33, when found advisable to counteract the excessive humidity.

During the operations above described it is to be remembered that each of the plurality of ovens may be operated as an independent element, and hence a different condition or step in the process may be carried on in different ovens at the same time and in this way permit the plant to be operated with a maximum efficiency. For example, the drying of the "daub" coating may be carried on in one or more of the ovens, while others are being utilized in the baking, drying or final drying and cooling of the skins, or any simultaneous combinations of these steps. Each oven is under the general control of heat or cold, but is also under independent control of temperature by its own heating coils 12. It will thus be seen that all of the operations necessary may be carried on at one time in the same set of ovens by merely adjusting the conditions required, and hence all of the workmen may be kept occupied.

The manufacture of the enameled and patent-leather may be conducted, irrespective of the atmospheric conditions; and the baking and drying may be carried on both day and night, so that no loss of time will occur waiting for favorable conditions, as heretofore, and which, with the impossibility of manufacturing with assurance of prompt delivery, reliability and uniformity of the finished product, has been the cause of many failures in business.

Where the saving in the turpentine from the varnish is not deemed desirable, as where the plant is small, then the condenser may be dispensed with, but in this case it is desirable during the baking operation to allow a portion of the turpentine laden air from the ovens to escape by the conduit 21 to the

chimney, and supply a corresponding quantity of fresh air into circulation by pipe 35 or otherwise. The speed of the process is largely dependent upon the elimination of the turpentine vapors from the circulating air and this should be done even at a sacrifice of some heat units necessary to raise the temperature of the incoming fresh air. Where the cost of fuel is low and saving in heat not important, then it is preferable to permit the entire baking and drying operations to be conducted with fresh air at the requisite temperatures. In this case, the turpentine vapors carried off in the baking operations, may be condensed by the condenser and the air allowed to escape by simply closing the valve 37 and opening the valve 36 in escape flue 38 in connection with the condenser. When this operation is carried on, all of the air which is to be heated may be taken in through pipe 35 when its valve 34 is opened.

I have shown my apparatus in the form which I have found most effective, and have described my improved process in the way I have preferred to operate under it in the commercial manufacture of enameled and patent-leather, but I do not restrict myself to the details of the apparatus, nor to the specific temperatures or time periods stated, as these may all be varied without departing from the spirit of the invention.

In this application, I do not make claim to the apparatus herein described as the same will form subject matter of a divisional application.

Having now described my invention, what I claim as new and desire to secure by Letters Patent is:—

1. The herein described method of manufacturing leather with an enameled surface from tanned skins having filled surfaces, consisting in coating a plurality of filled skins in stretched condition with varnish, placing the said stretched varnished skins within a closed oven with the skins arranged substantially horizontally and arranged one above the other, causing the varnish to set at a temperature insufficient to produce bubbles in the varnish, baking and drying all of the set varnished surfaces of the plurality of skins under the same conditions by subjecting said varnished surfaces simultaneously to equal currents of heated air and withdrawing the vapor laden air from the oven immediately after acting upon the leather, and finally lowering the temperature of the heated air after the baking of the varnished surface of the skins to insure thorough and complete drying and cooling of the same before removing the skins from the oven.

2. The herein described method of manufacturing leather with an enameled surface, consisting in placing stretched varnished

skins in a closed oven in horizontal position one above the other and in a quiescent condition, raising the temperature of the oven sufficiently to vaporize the volatile matters of the varnish but not burn the leather, circulating air horizontally between the stretched skins at the said temperature, and forcibly removing the vapor laden air from the oven until the leather is approximately baked and dried, then passing cooler air through the oven for lowering the temperature of the oven and cooling the skins and removing all tackiness thereof, and finally withdrawing the skins from the oven.

3. The herein described method of manufacturing leather with an enameled surface from a skin having a filled surface, which consists in varnishing the filled surface in stretched condition, arranging the stretched varnished skin in a horizontal position within a closed chamber, baking and drying the varnish by passing a current of air over the same at approximately 140 degrees or upward and during the baking operation removing the vapor laden air from the closed chamber and presence of the leather, and finally removing all tackiness from the dried varnished surface by passing a current of air at much lower temperature over the varnished skin for lowering its temperature and hardening the varnished surface.

4. The herein described method of manufacturing leather with an enameled surface from a tanned skin having a filled surface, consisting in varnishing the filled surface of the leather and placing it while sticky in a closed oven heated to a temperature sufficient to volatilize the more volatile portions of the varnish, causing a circulation of air through the oven and over the surface of the leather and thereby removing the vapors which escape from the varnish and transferring said vapors to a point outside of the oven to produce a greatly more dense and dry condition of the varnished surface, then raising the temperature of the partly dried leather and subjecting it to a continued current of air at the higher temperature until the varnished leather is thoroughly baked and dried, and finally removing the leather from the oven.

5. The herein described method of manufacturing leather with an enameled surface from a tanned skin having a filled surface, consisting in varnishing the filled surface of the leather and placing it while sticky in a closed oven heated to a temperature sufficient to volatilize the more volatile portions of the varnish, causing a circulation of air through the oven and over the surface of the leather and thereby removing the vapors which escape from the varnish and transferring them to a point outside of the oven, continuing this operation until the varnished leather is fully baked and approximately dried, and

finally removing the tackiness of the dried varnished leather by passing a current of cool air over the heated leather to lower the temperature of the oven and cool the leather 5 before removing the leather from the oven.

6. The method of making enameled leather, consisting in coating the leather with varnish, then placing the coated leather in a closed oven, then setting, baking and 10 drying the varnish by subjecting the leather successively to a medium temperature, a high temperature and finally to a low temperature, and for a greater period of time to the high temperature than to the medium 15 and low temperatures, and during the setting and baking operations removing the vapor laden air from the oven and supplying fresh heated air in its place.

7. The herein described method of manufacturing leather with an enameled surface, 20 consisting in baking and drying a varnished surface on the leather by causing a forced circulation of heated air to pass over the varnished surface and moving the vapor laden air out of contact with the leather, and regulating the temperature of the air during the baking and drying operations without disturbing the leather throughout its entire treatment.

In testimony of which invention, I here- 30 unto set my hand.

R. M. HUNTER.
